UNITED STATES PATENT OFFICE.

LOUIS DOMEYER, OF JOLON, CALIFORNIA.

SHOE.

1,232,010.

Specification of Letters Patent.

Patented July 3, 1917.

Application filed January 27, 1915. Serial No. 4,936.

To all whom it may concern:

Be it known that I, LOUIS DOMEYER, a citizen of the United States, residing at Jolon, in the county of Monterey and State of California, have invented certain new and useful Improvements in Shoes, of which the following is a specification.

This invention relates to improvements in shoes and has for its principal object the construction of a shoe having a flexible metal sole differing from the present metal shoes wherein the sole is more or less rigid due to the upstanding flange around the circumference thereof.

15 Another object of my invention is to provide an improved form of screw both for fastening a rubber heel thereto and to provide projections on the sole thereof.

With these and other objects in view my invention consists in the novel construction, combination and arrangement of parts as described in the following specification and more particularly pointed out in the appended claims.

25 Reference being had to the accompanying drawing forming a part of this specification,

Figure 1 is a view in perspective partly broken away showing a shoe constructed 30 in accordance with my invention.

Fig. 2 is a view in perspective of the metal sole, heel, and counter used in constructing my shoe.

Fig. 3 is a view in perspective of the in- 35 sole used in connection therewith.

Fig. 4 is a view in perspective showing the underside of the upper before attaching to the sole.

Fig. 5 is an enlarged view in section 40 through the screws used in the sole and heel.

Referring to corresponding parts by the same numerals of reference, 1 denotes in general the metal base on which the shoe is constructed, the same consisting of the 45 sole portion 2, and the heel portion 3, connected by the arch portion 5. The sole portion has formed around the edge thereof the upstanding flange 6, this flange extending to the arch 5 as far as the point 7.

50 Riveted or otherwise attached to the heel 3 and the rear portion of the arch 5 is the counter 8. The upper 18 of the shoe is formed continuous across the arch portion 19 and has at the heel and sole the extending strips 20 and 21, respectively, which 55 are adapted to be clamped between the heel

and a metallic band 11 extending around the heel and between flange 16 and band 10 extending around the sole and under arch 5. Under the arch, portion 19 of the upper 60 is riveted to the arch 5 by large flat headed rivets, the heads 23 being on the outside; likewise bands 10 and 11 are riveted to their supporting member by rivets. The insole 12 is positioned within the shoe to make the same conform with the sole of the foot to provide the cushion and insulating means therefor.

I prefer to provide the portion 3 with the rubber heel 19, this heel being attached to 70 3 by means of screws of the form shown in Fig. 6 and denoted by 13. These screws have a conical head with the usual slot 14 and screw threads 15 at the small end of the head, and the inner end is provided with a square socket 16. This socket is provided in order that when the head 13 wears down along with the heel the square socket is exposed and the stubs of the screws may be removed from the plate 3 75 by inserting a key in this socket allowing new heels held by new screws to be placed on the shoe. The sole is provided with hobs formed by the screws 17, this screw having a conical head 17, the screw in this case being formed on the base and provided with a socket 16 by which it is turned into place.

In use it will be readily understood that this construction gives a flexible construction due to the fact that the arch portion is 80 not provided with an upstanding flange, consequently, is free to flex during the walking movement.

While I have shown and described the preferred embodiment of my invention it 85 will be understood that minor changes in detail of construction may be resorted to without departing from the principles of the invention.

What I claim as new and wish to cover 90 by Letters Patent is:—

1. A shoe having a metallic bottom comprising a sole portion, a heel portion, a flexible arch connecting said sole and said heel portions, an upstanding flange formed 105 around said sole portion, a counter attached to said heel portion and the arch at a point adjacent said heel portion, and an upper extending under said arch and attached thereto by large flat headed rivets, for 110 attaching said upper to said arch.

2. A shoe having a metallic bottom com-

prising a sole portion, a heel portion, a flexible arch connecting said sole and said heel portions, an upstanding flange formed around said sole portion, a counter 5 attached to said heel portion and the arch at a point adjacent said heel portion, metallic strips surrounding said upstanding flange and said counter, and extending under said arch, an upper having a continuous 10 strip extending under said arch, and large flat headed rivets for attaching said upper to said arch, downwardly extending

flanges around said sole and heel portions of said upper adapted to be held by rivets between said metallic strips and the upstanding flange of said sole portion and the counter of said heel portions. 15

In testimony whereof I affix my signature in presence of two witnesses.

LOUIS DOMEYER.
